MUSICAL INSTRUMENT

Nils Arvid Palmgren, Gottenborg, Sweden

Application June 29, 1933, Serial No. 678,134
In Sweden July 28, 1932

4 Claims. (Cl. 84—1)

This invention relates to musical instruments associated with an electric sound reproduction system, and having a series of mechanical vibratory members tuned to acoustic frequencies and comprising electrically conductive material, an electrode disposed near such vibratory members and electrically insulated from them and forming therewith electrical condensers, the distance between electrode and vibratory member being different for different vibratory members.

10 In musical instruments having a number of vibratory members, such as strings or the like and electrically conductive plates or electrodes arranged adjacent thereto and forming together with the vibratory members, condensers serving to transform the vibrations of the strings to electrical impulses, it is of great importance that disturbing electrostatic fields are prevented from acting between the string and the electrode. Such electrostatic fields may reach an intensity comparable to that of the variations in strength of the field caused by the vibrations of the strings.

25 The object of the present invention is to eliminate the disturbances by electrostatically screening the electrodes, i. e. by enclosing them in a relatively tight system of bodies of constant potential.

30 The invention is illustrated in the accompanying drawing which:

35 Fig. 1 is a diagram showing the electrical arrangement of one form of the invention.

Fig. 2 is a plan view of the frame, the system of strings and the electrodes of a form of the invention, and

40 Fig. 3 is a section along the line 3—3 of Fig. 2. In Fig. 1 the numeral 1 denotes a string near which is located an electrode 2. The electrode is screened on one side by the string and on the other side by a member 3 electrically connected to the string. The string 1 is connected to the positive pole of a source of electrical current 4, the negative pole of which is connected to the electrode 2 through the resistance 5. The electrostatic fields between the electrode and the string 1 and between the electrode and the screen 3 cannot be disturbed by extraneous fields. The

connection 6 between the electrode 2 and the grid of the amplifier tube is also screened.

In the form of the invention illustrated in Figs. 2 and 3 a series of strings 9 are shown strung on a cast iron frame 8. The frame is therefore 30 in electrical contact with the strings. At a short distance from the strings are located two electrodes 10 and 11. As shown in Fig. 3 the electrode 10 comprises a layer 12 of metallic substance applied to a thicker plate 13 of electrically insulating material. The frame 8 is extended to form a plate 14 which covers the whole electrode and to which the electrode is adjustably fixed by means of adjusting screws 15 and 16. The electrostatic screen is here formed by the series of strings 9, the frame 8 and the plate 14 in conjunction. By fixing the electrode to the part 14 of the frame which screens the electrode the advantage is obtained that the distance between the string and the electrode can be accurately 65 adjusted and maintained independent of changes in temperature and humidity.

70 I claim

1. A musical instrument having a series of mechanical vibratory members and electrodes located near the said vibratory members and forming electrical condensers together therewith, and means for screening the electrodes.

2. A musical instrument according to claim 1 in which the screening means are electrically 80 connected to the vibratory members.

3. A musical instrument according to claim 1 in which the vibratory members comprise strings strung on a metallic frame, characterized in that the electrostatic screen on one side of the electrode is formed by the series of strings and on the other side by a part of the frame.

4. A musical instrument having a metallic frame, a series of vibratory strings strung thereon, a series of electrodes located adjacent the strings, the series of strings forming an electrostatic screen on one side of the electrodes and a part of the frame forming a screen on the other side thereof, and adjusting screws for fixing the electrodes to that part of the frame which serves 90 to screen them.

95 NILS ARVID PALMGREN.
